UNITED STATES PATENT OFFICE.

SAMUEL LIPPERT, OF EAST CLEVELAND, OHIO.

ROTARY DEEP-WELL PUMP.

1,239,706.

Specification of Letters Patent. Patented Sept. 11, 1917.

Application filed July 24, 1913. Serial No. 780,873.

To all whom it may concern:

Be it known that I, SAMUEL LIPPERT, a citizen of the United States, and resident of East Cleveland, in the county of Cuyahoga and State of Ohio, have invented certain new and useful Improvements in Rotary Deep-Well Pumps, of which I hereby declare the following to be a full, clear, and exact description, such as will enable others skilled in the art to which it appertains to make and use the same.

This invention relates to pumps and more particularly to pumps of the rotary inclined vane type, and has for its general objects to provide an efficient pump of this type capable of forcing water or other fluids from one level to a level which may be greatly elevated above the former level; which will be practically continuous in operation; which will be particularly free from liability to become clogged or obstructed, and which is so constructed as to operate efficiently under all ordinary incidents of use. While capable of use in other environments, it is particularly well adapted for forcing liquids from extremely deep wells, such as oil wells and wells employed for irrigating purposes.

In the drawings forming part hereof,— Figure 1 represents a vertical sectional view of a well having my pump applied thereto, the pump being shown as operated by an electric motor;

Fig. 2 is a vertical sectional view, the parts above the pump chamber corresponding to the line 2—2 of Fig. 3.

Fig. 3 is a sectional view corresponding to the line 3—3 of Fig. 2;

Fig. 4 is a detail in perspective of the lower end of the pump shaft;

Fig. 5 is a sectional view corresponding to the line 5—5 of Fig. 3;

Figs. 6 and 6^a are sectional details of the pump tube, the shaft being shown in elevation; and

Fig. 7 is a view similar to Fig. 1 showing the pump shaft driven by a windmill.

Describing by reference characters the various parts illustrated herein, A denotes a well shaft having therein the pumping tube B. C denotes a cylindrical pump barrel connected at its upper end to the tube B by means of a coupling D and connected at its lower end by a coupling E to a suction tube E' having a strainer E².

Within the tube B is the pump shaft F

having at its lower end, within the barrel C, a hub F' which carries a pair of helical pumping vanes G, each less than 180° in angular extent—approximately 120°—whereby said vanes are circumferentially spaced, each vane having its upper and lower edges substantially horizontal, as shown at H, to coöperate with the corresponding walls of the pump chamber.

The lower end of the pump shaft is provided with a bearing I coöperating with a bearing I', there being balls J interposed between said bearings.

The lower bearing is seated on the bottom of a recess formed within the closure K for the bottom of the pump chamber. This closure is seated between the top L of the coupling E and a shoulder L' formed within the barrel C and is provided with a pair of induction ports M spaced 180° apart.

The hub F' and its vanes G rotate in the pump chamber N provided within the casting C between the closure K and a vertically spaced closure O which is seated upon the shoulder P.

The closure O is provided with eduction ports Q, Q, opposed to each other and spaced about 90° each from opposed induction ports M, M, and provided each with a gravity-seating ball-valve R coöperating with a seat R' and operating within a cage S.

Closely adjacent to each port M is a vertically sliding blade T, said blades being mounted within guideways provided within the closure O. These blades each extend radially outwardly from the hub F' into engagement with the inner wall of the pump chamber N and each is so shaped at its lower end as to form a substantially fluid-tight joint with the upper surface of each vane. These blades, as the pump shaft rotates, provide with the closures, the inner wall of the pump chamber, and the vanes, two chambers of constantly decreasing area from which the liquid sucked in from the ports M is forced into the pump tube. As the vanes rotate, they elevate the blades until the lower ends of the latter ride upon the plane surfaces H at the tops of the vanes. As soon as the vanes pass beneath the blades, the latter are quickly forced to the bottom of the pump chamber by means of springs U mounted in tubular extensions V of the blade guideways.

By inspection of Fig. 3 it will be apparent that, although each vane is of less than

180° in angular extent, the blade engaging edge and the blade-discharging edge of each vane is 180° from the corresponding edges of the other vane, so that the blades will be engaged, lifted, and dropped in like phase by each vane.

It will also be observed that the construction and arrangement of the vanes is such that a large chamber is provided for the 10 entering water at the instant when a blade is dropped from the discharge end of its vane. This, of course, tends to a maximum pump-capacity for a pump chamber of a given volume. However, because no intervening wall is interposed between the induction and eduction ports during the intervals between the dropping of a blade by one vane and its engagement by the other, it will follow that, but for the check valves R, the 15 20 25 pump chamber would be subjected to the head of the water in the pump tube B during such intervals. By the provision of the valves R, I am enabled to operate the pump continuously, at maximum capacity, and without detrimentally affecting the supply of the liquid to the pump chamber.

For the purpose of supporting the pump shaft within the tube B, spiders W are provided at suitable intervals,—see Fig. 7.

30 Having described my invention, what I claim is:

1. In a pump, the combination of a cylindrical pump chamber provided with induction ports leading into the bottom thereof and with eduction ports leading from the top thereof, a vertically extending pump tube whereinto the eduction ports are adapted to discharge, check valves for the eduction ports and adapted to relieve the 35 40 45 50 pump chamber from the pressure of the liquid in the tube thereabove, rotary helical vanes in said chamber corresponding to said eduction ports, said vanes being circumferentially spaced, blades slidably mounted in the top of the said chamber adjacent to said eduction ports and adapted to be elevated by said vanes, means for projecting said blades downwardly to the bottom of said chamber when released by said vanes, and means for rotating said vanes.

2. In a pump, the combination of a cylindrical pump chamber provided with induction ports leading into one end thereof and with eduction ports leading from the other 55 60 65 end thereof, a vertically extending pump tube communicating with the eduction ports, check valves controlling the eduction ports and adapted to relieve the pump chamber from the pressure of the liquid in the tube thereabove, rotary helical vanes in said chamber corresponding to said eduction ports, said vanes being circumferentially spaced, blades slidably mounted in guideways in the delivery end of the pump chamber adjacent to the eduction ports, tubular

extensions for said guideways, springs in said extensions tending to thrust the blades toward the induction end of the pump chamber, and means for rotating said vanes.

3. In a pump, the combination of a cylindrical pump chamber provided with induction ports leading into one end thereof and with eduction ports leading from the other end thereof, a vertically extending pump tube communicating with the eduction ports, 70 means for relieving the pump chamber from the pressure of the liquid in the tube thereabove, rotary helical vanes in said chamber corresponding to said eduction ports, said vanes being circumferentially spaced, blades 80 slidably mounted in the delivery end of the pump chamber, means for moving the blades toward the induction end of the pump chamber, and means for rotating said vanes.

4. In a pump, the combination of a cylindrical pump chamber provided with induction ports leading into one end thereof and with eduction ports leading from the opposite end thereof, a vertically extending pump tube whereinto the eduction ports 90 are adapted to discharge, cages projecting from the end of the pump chamber carrying the eduction ports, balls in said cages adapted to relieve the pump chamber from the pressure of the liquid in the tube thereabove, rotary helical vanes in said chamber corresponding to said eduction ports, said vanes being circumferentially spaced, blades 95 slidably mounted in guideways in the eduction wall of the pump chamber adjacent to the eduction ports and adapted to be moved by said vanes, tubular extensions to said guideways carried by the eduction wall, springs in said extensions adapted to move the blades toward the induction end 100 of the pump chamber, and means for rotating said vanes.

5. In a pump, the combination of a cylindrical pump chamber having a wall at each end thereof, one of said walls being provided with an induction port and the other with an eduction port, a vertical pump tube extending from the wall having the eduction port, a shaft extending through said chamber and having a bearing, a coöperating bearing in the wall having the induction port arranged within a recess within said wall, there being antifriction devices interposed between said bearings in said recess, a helical vane carried by said shaft 110 within said chamber, said vane being of less than 360° in angular extent, a blade slidably mounted in the wall having the eduction port and adapted to be operated in one direction by said vane, means coöperating 115 with said blade for operating it in the reverse direction, means coöperating with the eduction port to relieve the pump chamber from the pressure of the water in said tube, and means for rotating said shaft. 120 125 130

6. In a pump, the combination of a vertical cylindrical pump chamber having a wall at each end thereof, the bottom wall being provided with angularly spaced induction ports and the top wall with angularly spaced eduction ports, a vertical pump tube extending from the top wall, a shaft within said tube and extending through the pump chamber and having a bearing, a co-operating bearing in the bottom wall arranged within a recess within said wall, there being anti-friction devices interposed between said bearings in said recess, helical vanes carried by said shaft in said chamber, said vanes being circumferentially spaced and each vane being of less angular extent than the distance between adjacent eduction ports, blades slidably mounted in the upper wall and each arranged adjacent to an eduction port and adapted to be operated in one direction by said vanes, means co-operating with said blade for operating it in the reverse direction, means co-operating with the eduction ports to relieve the pump chamber from the pressure of the water in said tube, 25 and means for rotating said shaft.
7. In a pump, the combination of a cylindrical pump chamber having end walls, there being an induction port in one of said walls and an eduction port in the other of 30 said walls, a vertical pump tube extending from the second of said walls, a rotary helical vane within the pump chamber, said vane being of less than 360° in angular extent, a blade slidably mounted in the second 35 end wall and adapted to be operated in one direction by said vane, means for operating said blade in the reverse direction, means for relieving the pump chamber from the pressure of the water in the tube there- 40 above, and means for rotating said vane.

In testimony whereof, I hereunto set my hand this 21st day of July, 1913.

SAMUEL LIPPERT.
